H. W. GOFF

SWAGING TOOL

Filed Feb. 10, 1923

Inventor:
Harold W. Goff,

by *P.W. Adams Atty.*

UNITED STATES PATENT OFFICE.

HAROLD WHEELER GOFF, OF NEW YORK, N. Y., ASSIGNOR TO WESTERN ELECTRIC COMPANY, INCORPORATED, OF NEW YORK, N. Y., A CORPORATION OF NEW YORK.

SWAGING TOOL.

Application filed February 10, 1923. Serial No. 618,215.

To all whom it may concern:

Be it known that I, HAROLD W. GOFF, a citizen of the United States of America, residing at New York, in the county of New York and State of New York, have invented certain new and useful Improvements in Swaging Tools, of which the following is a full, clear, concise, and exact description.

This invention relates to improvements in the method and means for adjusting certain operating parts of light machinery.

More particularly it refers to a measuring fixture and swaging tool for adjusting the operating members such as are used in the selecting mechanism of coordinate switches of the type disclosed in the British patent to Western Electric Company, Limited, No. 197,891, accepted May 24, 1923.

In such mechanism it is necessary to adjust just by a bending operation, a relatively great number of parts which are generally made of relatively thin sheet metal of such a width that they do not easily yield to a force applied to bend them in that plane.

The object of this invention is the provision of a simple and efficient adjusting tool for adjusting the parts of mechanisms of the type to which reference has been made.

A feature of the tool resides in the provision of a pair of special jaws attached to compound lever pliers by means of which indentures are made along the edges of the part to be adjusted. Another feature is the provision of a stop attached on one of the jaws and adapted to assist in positioning the swaging tool with respect to the part to be adjusted and to limit the extent of the indenture to be effected thereon.

A feature in the measuring fixture is the provision of a graduated index which is common to a plurality of operating members and by means of which the adjustment of each of said operating members is easily ascertained.

Another feature in the measuring fixture is the provision of locating means for the support of the operating members by means of which its exact location relative to the index is readily secured.

The invention will be more readily understood by the following description and by the claims appended thereto, reference being had to the accompanying drawings in which Fig. 1 is a plan assembly view of the swag-

ing tool shown with its jaws opened and the stop overlapping the cams, Fig. 2 is a front assembly view of the swaging tool showing a part to be swaged positioned between the cams, and Fig. 3 is a perspective and partial view of the fixture used in connection with the swaging tool showing a graduated index, a face plate supporting the same and a portion of a bar on which the lifting fingers are secured shown in adjusted position on the plate.

The swaging tool shown in Fig 1 comprises an ordinary pair of compound pliers designated by the reference character A. On the jaws 8 and 9 of said pliers are securely attached a pair of swages 10 and 11. The stop 14 is secured on the swage 10 by means of the screws 15 and 16 and its free end is adjusted to extend over the central portion of its cooperating swage 11. The stop 14 is provided to assist in positioning the swaging tool on the part 35 to be adjusted and to limit thereon the extent of the indenture to be impressed, in order to bend the free end portion of said part toward its respective orientation point.

The measuring fixture contemplated for use in connection with the above described swaging tool is shown in Fig. 3 and comprises preferably an oblong apertured face plate 16 on one edge of which the graduated index 17 is secured by means of screws 18, etc.

The graduation marks 27, 28, etc. made along the index 17 are adapted to indicate the parallel adjustment of lifting fingers 29, 30, etc., when assembled on the operating bar 20. This bar 20 which in connection with the coordinate switch is generally referred to as link bar, has a number of locating holes drilled at intervals and which register with similarly spaced holes drilled along the opposite edge of the fixture and in which the pins 23 are inserted for the purpose of properly positioning the bar and lifting fingers thereon with reference to their respective marks on the index 17. In addition to locating pins 23, etc., the bar 20 is held in adjusted position on the fixture plate 16 by means of a number of screws 22, etc. In that adjusted position, if it is supposed that the operating members have been correctly assembled on the bar, their pointed end portions 24, 24', will be in juxtaposition

with the pointed edge 25 of the common index 17 and their respective graduation marks, as shown by Fig. 3. If, however, any one of the operating members deviates from its adjusted position for example, as indicated by the dotted line at B, an indenture is impressed along the edge of said member as shown at 26 which has for result the bending of said part 35 toward its adjusted position through the spreading of the metal in that portion. If the end of the finger 24 registers with the edge 25 but not with the index line 28, then a simple bending operating at right angles to the plane of the finger will bring it into its proper position.

What is claimed is:

1. A device for adjusting sheet metal strips comprising a pair of pliers, a swage attached to each jaw of said pliers for spreading the metal along one edge to cause its free end portion to bend toward a predetermined position, and means carried by

one of said swages to assist in positioning said device.

2. A swaging tool comprising a pair of compound lever pliers, a swage attached to each jaw of said pliers, and means carried by one of said swages to assist in positioning said tool on the material to be swaged, preparatory to its adjustment by means of said swages.

3. A swaging tool comprising a pair of compound lever pliers, a swage attached to each jaw of said pliers, said swages being arranged with their top cooperating edges diverging from a common apex, and means carried by one of said swages to assist in positioning said tool on the material to be swaged preparatory to its adjustment by means of said swages, so that said apex will appear beyond the limits of the material.

In witness whereof, I hereunto subscribe my name this 5 day of February A. D., 1923.

HAROLD WHEELER GOFF.
